UNITED STATES PATENT OFFICE.

HARRY WALTER STERTZBACH AND MERRITT RASMUS HANSEN, OF COLUMBUS, OHIO,
ASSIGNORS TO THE BUCKEYE STEEL CASTINGS COMPANY, OF COLUMBUS, OHIO.

CAR-TRUCK SIDE FRAME.

Application filed March 11, 1925. Serial No. 14,782.

This invention relates to car truck side frames of that type in which the entire frame is cast as a single integral structure exemplified in Letters Patent No. 1,523,793, 5 granted to us January 20th, 1925, and No. 1,378,794 granted to George T. Johnson and Harry W. Stertzbach May 17th, 1921, and has special reference to the formation of the connection between the spring seat and the 10 tension member. In the side frames to which this invention is applied, the transverse horizontal webs of the tension members form a continuous element with the top plate of the spring seat, which top plate 15 is relatively widened to properly support the superimposed springs. The widened portion of the plate is a part of the tension member and, due to bending, it is subjected to localized stress at the ends of the 20 spring seat. This widened plate is most effectively utilized by keeping it aligned with the web of the tension member. One object of the present invention is to provide a construction which will effectively withstand 25 this localized tensile stress.

In the manufacture of steel castings it is highly desirable to avoid enlargement or so-called "wads" of metal that are caused by two or more members meeting on a common line or at a common point. These "wads" necessitate the use of chills to prevent shrinkage which adversely affect the soundness of the casting. Another object of the invention, therefore, is to avoid the formation 30 of "wads" in the casting. The invention will be hereinafter fully described with reference to the accompanying drawing, and consists in certain novel features which will be particularly pointed out in the appended 35 claims.

In the drawing, Figure 1 is a side elevation of so much of a side frame as is necessary to an understanding of the invention;

Figure 2 is a top plan view of the same;

Figure 3 is a transverse section on the line 3-3 of Fig. 1;

Figure 4 is a view similar to Figure 3 but showing a slightly different embodiment of the invention;

Figure 5 is a bottom plan view showing a form differing from the forms shown in the preceding figures;

Figure 6 is a horizontal section taken in the plane indicated by the line 6-6 in Fig-

ure 1 but showing the construction indicated 55 in Figure 5.

Figure 7 is a transverse section corresponding to Figure 3 but showing the form of Figure 5;

Figure 8 is a transverse section showing 60 a form differing somewhat from Figure 7.

In the drawing, 1 designates the tension member, 2 the spring seat, and 3 the column at the side of the spring seat. As indicated at 4, the top plate or shelf of the spring seat 65 is expanded laterally or widened to furnish an adequate support for the springs, and the end portions of the shelf gradually decrease in width and merge into the top plate or web of the tension member approximately at the 70 base of the column. In casting the frame, "wads" tend to form at the junction of the column with the spring seat and the tension member at the point marked 5 in Figs. 1 and 3. With the ordinary construction, these 75 wads extend across the entire width of the spring seat and also extend longitudinally of the frame. We form an opening 6 in the web of the column at the lower end thereof and thereby eliminate the "wad" to the extent of the total width of the lower end of the opening, and the outstanding ribs or flanges 7 are provided on the sides of the column to furnish strength to meet transverse forces applied to the column. We also arrange the depending side walls 8 of the spring seat in outwardly offset relation thereby rendering the longitudinal extent of the "wad" negligible. The lower edges of the side walls 8 are preferably connected by a 80 horizontal web 9 forming a box under the spring seat which may have a trapezoidal or other cross section, as long as the offset relation of the walls to the sides of the column 85 is maintained. The bottom connecting web may even be omitted. This disposition of the depending side walls reduces the overhang of the shelf so that it may resist the tendency to curl upward under load. It also makes it possible to omit the outstanding 90 flanges 7 when desired, the requisite strength in the column being maintained by reducing the width of the opening 6 and forming integral ribs 10, as shown in Fig. 4. Inasmuch as the "wad" is most injurious at the 95 point where the spring seat and the transverse web of the column unite, the value of the offset formation lessens toward the ends 100

105

of the frame and it becomes desirable to converge the offset depending side walls into the more narrowly spaced side walls of the inverted channel form of the tension member, as indicated at 11.

In Figs. 5 to 7 inclusive, the extreme width of the column 3 at its lower end is somewhat greater than the width of the tension member. The side walls of the box under the 10 spring seat are vertical but the side walls 12 of the column are offset relative thereto so that the longitudinal wad is very materially reduced, the transverse wad being minimized by the provision of the opening 6. In Fig. 15 7, the opening 6 is less than the full width of the column while in Fig. 8 the opening is as wide as the box and the increased width of the column takes the form of external ribs 18 which strengthen the web 4 of the spring 20 seat.

Having fully described our invention what we claim as new and desire to secure by Letters Patent, is:—

1. A cast side frame for car trucks including a tension member, a spring seat merging into the tension member, a column rising vertically from the spring seat at the junction of the same with the tension member, and longitudinally extending depending side 25 walls on the bottom of the spring seat, said 30

walls being offset relative to the sides of the column.

2. A cast side frame for car trucks including a tension member the lower end of which is of inverted channel formation in cross section, a spring seat having a longitudinal box or channel section on its under side merging at its ends into the channel of the tension member, and a column rising vertically from the spring seat at the junction of the same 35 with the tension member, the sides of the column being offset relative to the sides of the box or channel section and there being an opening through the column immediately at 40 the spring seat.

3. A cast side frame for car trucks including a tension member, a vertical column, and a spring seat merging into the tension member at the base of the column, there being an opening through the column at the spring 45 seat and the spring seat having a longitudinal box or channel section on its under side, the side walls of the box or channel section having their upper edges offset relative to the 50 sides of the column.

In testimony whereof, we have signed this specification.

HARRY WALTER STERTZBACH.
MERRITT RASMUS HANSEN.
